UNITED STATES PATENT OFFICE.

JOSEPH ANSON, OF MADOC, ONTARIO, CANADA, ASSIGNOR OF ONE-THIRD TO WILLIAM SLEEMAN AND ONE-THIRD TO THOMAS SLEEMAN, BOTH OF BESSEMER, ONTARIO, CANADA.

ACETYLENE-LAMP.

1,060,660.

Specification of Letters Patent.

Patented May 6, 1913.

Application filed September 23, 1912. Serial No. 721,756.

To all whom it may concern:

Be it known that I, JOSEPH ANSON, a citizen of the United States of America, residing at Madoc, Province of Ontario, 5 Canada, have invented certain new and useful Improvements in Acetylene-Lamps; and I do hereby declare that the following is a full, clear, and exact description of the invention, such as will enable others skilled in 10 the art to which it appertains to make and use the same.

The invention to be hereinafter described relates to miners' acetylene lamps.

In order to more clearly disclose the construction, operation, and use of the invention, reference should be had to the accompanying drawings forming part of the present application.

Throughout the several figures of the 20 drawings like reference characters designate the same parts.

In the drawings: Figure 1 is a front, central, vertical, sectional view of a lamp embodying my invention, one of the carbid 25 cartridge casings being shown in side elevation; Fig. 2 is a top plan view of a carbid cartridge; Fig. 3 is a top plan view of a cylinder adapted to contain the carbid cartridge with the cap removed; Fig. 4 is a 30 front view of the gas jet and a portion of the lamp, showing position of the reflector; Fig. 5 is a front view of the rod used to clear the gas tube.

Referring to the drawings in detail; the 35 numeral 1 designates the body of the lamp, which is composed of two parts, an upper part 2 and a lower part 3 secured together by means of screw threads 4. The upper part 2 contains a water chamber 5 provided 40 with a rounded top 6 screw threaded as at 7 for filling purposes, and the lower part 3 contains a gas chamber 8. Integral with the bottom of the lower part 3 is a tubular part 9 cut away at its upper central part as at 10 45 and adapted to receive in either end a cylindrical casing 11. The said casing 11 when in operative position projects into the tubular part 9 a slight distance beyond the longitudinal center of the said tubular part, 50 and is provided with an internally screw threaded cap 12 on its outer end and an opening 13 in its upper side, at its inner end. The said casing 11 is made of such a size as to be a push-fit into the tubular part

9. A cartridge 14 corresponding in size and 55 shape to the interior of the casing 11 is provided, having an opening 15 at its inner end corresponding in size and shape to the opening 13 in the said casing and adapted to be matched therewith. The said cartridge 14 60 is filled with crushed carbid 16, a transparent covering 17 such as oiled paper or other suitable material being provided for the opening 15 to enable the user to determine if the cartridge is filled. A movable 65 gasket 18 is provided at the proximate center of the tubular part 9 of less interior diameter than the exterior diameter of the casing 11 so that when one of the cylindrical casings is inserted in one end of the said 70 tubular part its inner end engages the said gasket and pushes the casing already in the said tubular part out of the other end far enough to enable the user to secure a good grip on the outer end of the said casing so 75 as to extract it from the lamp. This gasket also serves to make an air tight closure over the outer part of the opening 10 not covered by the end of the casing 11, as shown in Fig. 1. 80

A tube 19 extending downwardly from the inner under face of the rounded top 6 of the water chamber 5 to a point in the gas chamber 8 about two thirds of the distance from the top to the bottom thereof is provided at the center of the lamp. The tube 19 is secured through the bottom 20 of the water chamber 5 by soldering or other suitable means, and is provided with a small hole 21 in its front a slight distance above 90 the bottom of the water chamber, a tubular arm 22 on each side near the lower end integral therewith and at a considerable angle thereto, and a hole 23 in its lower end. The tube 19 contains a rod 24 provided with a 95 thick washer 25, near its lower end, of slightly less diameter than the interior of said tube. The lower end 26 of the said rod projects through the bottom of the tube 19 and operates vertically in the hole 23, being 100 slightly smaller in cross section than the said hole. The upper end of the rod 24 projects through the top 6 of the water chamber 5, being fitted so tightly through the cap as to allow no gas to escape, and is 105 provided with a ring 27 to form a finger grip. A gas jet 28 is connected to the front of the tube 19 a slight distance below the

water chamber, and provided with a concave reflector 29 fitting around the said gas jet as shown in Fig. 4.

On the back of the lamp is the usual hook 5 33, and the lamp is also provided with a grip 34 attached to the top 6 of the water chamber 5.

The operation is as follows: The water enters the central tube 19 through the small 10 hole 21 and trickles down the front inner face of the tube. The water collects in the lower part of the tube around the washer 25 and drops down as shown by the arrow Fig. 1 on to the crushed carbid 16. As the gas 15 collects the pressure created forces it through the arms 22 and up the tube 19 into the gas jet 28. As the top of the tube 19 is closed so as to be air tight there is no other way for the gas to escape except through the said 20 gas jet. To clear the tube 19 the rod 24 is worked up and down the washer 25 serving to dislodge any dust and thus keep the tube open at all times. As the water trickles down the front inner face of the tube 19 and 25 the gas enters the tube from the sides and above the washer 25 where the water collects there is no chance for the water to interfere in any way with the flow of the gas. When the carbid in one cartridge has been 30 exhausted, the lamp may be recharged by placing another cartridge in a casing and inserting the casing into the tubular part through the open end, first breaking and tearing out the covering 17 of the hole 15 in 35 the cartridge. The inner end of the casing 11 engages the inner end of the gasket 18 pushing it forward against the casing already in the lamp and thus forces the said casing out as in Fig. 1. The gasket 18 is 40 made of such a width as to effectually close the part of the opening 10 not covered by the inner end of the tube 11, and thus prevent any gas from escaping from the chamber 8. The gas stored in the chamber 8 is 45 sufficient to keep the lamp burning while being recharged; as the recharging requires only a few seconds.

It is thought that the construction, operation, and use of the invention will be clear 50 from the preceding detailed description.

Changes may be made in the construction, arrangement, and disposition of the several parts of the invention without in any way departing from the field and scope 55 of the same, and it is meant to include all such within this application wherein only a preferred form has been disclosed.

Having thus fully described my invention, what I claim as new and desire to secure by 60 Letters Patent is:

1. In combination in a device of the character described, a gas chamber, a horizontal tubular casing integral therewith and open at both ends and having an opening in the longitudinal center of its upper face 65 communicating with the gas chamber, a gasket slidably mounted in the central portion of the tube, a carbide containing casing adapted to be inserted into one end of the tube and of such length as, in combination 70 with the gasket, to completely close the opening between the tube and the gas chamber.

2. In a device of the character described means for recharging the lamp without extinguishing, comprising; a gas chamber, a horizontal tubular casing integral therewith and open at both ends, and having an opening in its upper face communicating with the gas chamber, a carbide containing casing 75 adapted to be inserted into operative position for generating purposes in one end of the tube, a gasket carried in the tubular casing and adapted to coact with the carbide containing casing to completely cover the 80 opening between the gas chamber and the tubular casing; and a second carbide containing casing identical with the first mentioned casing and adapted to be inserted into the tubular casing from the opposite end 85 thereof when the carbide carried by the first mentioned casing is used and thus force the first casing outwardly by engaging the gasket and forcing it outwardly until the gasket occupies the same relative position to the 90 second mentioned casing as it did to the first mentioned casing.

3. In a device of the character described recharging means, comprising; a gas chamber; a tubular casing carried thereby and 100 communicating therewith, a gasket carried in the tubular casing, a carbide cartridge inserted into one end of the casing and adapted to coact with the gasket to shut off communication between the gas chamber and tubular casing, and a second carbide cartridge identical with the first and adapted 105 to be inserted into the opposite end of the tubular casing and to coact with the gasket to force the first mentioned cartridge outwardly until the gasket and the second cartridge occupy the same relative positions to the gas chamber and to each other, as the first mentioned cartridge and the gasket did.

In witness whereof I have hereunto set my 115 hand in the presence of two witnesses.

JOSEPH ANSON.
